UNITED STATES PATENT OFFICE

115,321

DESIGN FOR A BIRD FEEDING STATION

Paul Pueschel, Glencoe, Ill.

Application April 19, 1939, Serial No. 84,384

Term of patent 7 years

To all whom it may concern:

Be it known that I, Paul Pueschel, a citizen of the United States, residing at Glencoe, in the county of Cook, State of Illinois, have invented a new, original, and ornamental Design for a Bird Feeding Station, of which the following is a specification, reference being had to the accompanying drawing, forming a part thereof, wherein the figure of the drawing is a perspective view of a bird feeding station showing my new design.

I claim:

The ornamental design for a bird feeding station, as shown.

PAUL PUESCHEL.
